UNITED STATES PATENT OFFICE.

RUDOLPH HOFFMAN, OF CHICAGO HEIGHTS, ILLINOIS, ASSIGNOR TO SEARS, ROEBUCK AND COMPANY, OF CHICAGO, ILLINOIS, A CORPORATION OF NEW YORK.

BLUE-FLAME WICK OIL-BURNER.

1,183,979.

Specification of Letters Patent.

Patented May 23, 1916.

Application filed March 31, 1915. Serial No. 18,210.

To all whom it may concern:

Be it known that I, RUDOLPH HOFFMAN, a citizen of the United States, residing at Chicago Heights, in the county of Cook and 5 State of Illinois, have invented certain new and useful Improvements in Blue-Flame Wick Oil-Burners, of which the following is a specification.

In blue-flame wick oil burners, the annular wick is vertically movable within an annular casing formed of an inner and an outer wick tube. As the power for raising and lowering the wick is applied at one point only, there is a tendency for the wick 10 to tilt and bind and thus either to become locked in its annular casing or to rise unevenly. This tendency is especially apt to manifest itself when the interior diameter of the wick is somewhat greater than normal.

The object of this invention is to provide simple and effective means for obviating this difficulty.

In the accompanying drawings, Figure 1 25 is a vertical central sectional view through the annular wick casing and the wick, the wick-raising means also being illustrated. Fig. 2 is a fragmental sectional view upon an enlarged scale.

30 The inner wick tube 1 and the outer wick tube 2 are secured together at their lower ends and form an annular casing 3. The lower end of the casing 3 communicates in any suitable or well-known way with an oil supply pipe. The upper end of the outer wick tube is slightly contracted, and the upper end of the inner wick tube is slightly flared, so that said tubes shall properly conform to the wick.

40 The wick 4 is secured to a wick carrier 5 which consists of a sleeve or ring of sheet-metal encircling the major portion of the wick. The lower edge of said ring is bent inwardly and upwardly into clamping engagement with the lower end of the wick, as at 6.

In the process of manufacture, the wick is placed within the wick carrier; the lower end of the carrier is folded inwardly to

form the roll 6; the upper end of the wick 50 carrier is annularly indented, thus forming an inwardly extending rib 7; and a plunger of the same diameter as the interior diameter of the roll 6 is forced into the wick, thus bringing the inside diameter of the wick in 55 the region of the rib 7 to the same dimension as the inside diameter of the roll 6. The diameter of said plunger is the same as the outside diameter of the flared upper end of the inner wick tube. 60

The wick carrier 5 has a plurality of perforations 8 adapted to receive the teeth of two spur wheels 9, said spur wheels being fixed to a shaft 10 which is provided with a hand-wheel 11. By turning the hand-wheel 65 11 the wick carrier and the wick may be raised and lowered in the casing 3.

The roll 6 and the portion of the wick which is pressed inwardly by the rib 7 provide bearing portions above and below the 70 wick-raiser wheels 9, said bearing portions being caused to bear against the inner wick tube by the pressure of the wheels. The interior diameter of said bearing portions being equal, the wick is prevented from tilt- 75 ing.

I claim as my invention:

1. In combination, an inner and an outer wick tube, a wick and a wick carrier in the space between said tubes, and a wick raiser 80 arranged to engage the wick carrier, the lower portion of said wick carrier below the wick raiser being inwardly folded to form a portion lying at the inner side of the wick and adapted to bear against the inner 85 wick tube, the upper portions of said wick and wick carrier above the wick raiser being shaped to form an inwardly extending portion adapted to bear against the inner wick tube. 90

2. In combination, an inner and an outer wick tube, a wick and a wick carrier in the space between said tubes, and a wick raiser, the lower portion of said wick carrier being inwardly folded to form a portion adapted 95 to bear against the inner wick tube, the upper portion of said wick carrier being annularly indented so as to decrease the inte-

rior diameter of the wick in the region of the indentation to the same dimension as the interior diameter of the folded portion of the carrier, the wick carrier being provided between said folded portion and indented portion with perforations for engagement by the wick raiser.

In testimony whereof, I hereunto set my hand in the presence of two witnesses.

RUDOLPH HOFFMAN.

In the presence of—
H. A. BARSCHOW,
BERTHA ARKENBERG.
